LIQUEFIER BOWL

Walter E. Moore, St. Louis, Mo., assignor to Knapp-Monarch Company, St. Louis, Mo., a corporation of Delaware

Application September 6, 1955, Serial No. 37,796

Term of patent 14 years

(Cl. D89—1)

Fig. 2

Fig. 1

Fig. 3

Fig. 4

Figure 1 is a side elevational view of a liquefier bowl showing my new design;

Figure 2 is a top plan view thereof;

Figure 3 is a side elevational view taken from the left of Figure 1; and

Figure 4 is a bottom view of the liquefier bowl.

I claim:

The ornamental design for a liquefier bowl, substantially as shown.
